(57) **CLAIM**

The ornamental design for a portion of air conditioner as shown and described.

DESCRIPTION

1. Portion of air conditioner

1.1 : Top, front, right-side perspective view

1.2 : Bottom, front, left-side perspective view

1.3 : Front

1.4 : Back

1.5 : Left

1.6 : Right

1.7 : Top

1.8 : Bottom

1.9 : Reference view

This article is a frame-type air conditioner; the broken lines shown in reproductions 1.1 to 1.8 depict portions of the air conditioner that form no part of the claimed design; reproduction 1.9 shows a state of use with the front panel being combined and forms no part of the claimed design; the shading lines are used to show the surface of the claimed design and do not represent its surface ornamentation.

1 Claim, 9 Drawing Sheets
